UNITED STATES PATENT OFFICE.

JOHN W. CULP, OF ELKHART, INDIANA.

GAME AND APPARATUS THEREFOR.

No. 833,779.

Specification of Letters Patent.

Patented Oct. 23, 1906.

Application filed December 26, 1905. Serial No. 293,367.

To all whom it may concern:

Be it known that I, JOHN W. CULP, residing at Elkhart, in the county of Elkhart and State of Indiana, have invented certain new and useful Improvements in Games and Apparatus Therefor, of which the following is a specification.

My invention relates to a certain new and useful game and game apparatus therefor which combines amusement, instruction, and exercise for young and old and which can be played by any number of persons. This game will be designated on the market as the game of "Pan ball," and the apparatus with which it is played comprises in its generic nature a receptacle in which a ball can be rotated to engage certain registering mechanism as it is rolled around the receptacle to positively indicate the number of times the ball performs certain impacting functions on the operating-levers of the registering mechanism.

In its more subordinate nature my invention comprises a pan or receptacle, having a bottom and an annular wall projecting upwardly therefrom and terminating in a ball-retaining rim, and a pair of registering devices mounted on the receptacle-wall and having operating-levers projected into the path of the moving ball, one of which levers is adapted to be engaged by the ball at each revolution thereof around the axis of the pan, while the other operating-lever is only engageable by the ball at certain predetermined times under control of the operator.

With other objects in view than have been heretofore specified the invention also embodies certain new construction, operation, and arrangement of parts of the apparatus, all of which will be first described in detail and then be specifically pointed out in the appended claims, reference being had to the accompanying drawings, in which—

Figure 1 is a perspective view of my invention applied for use when suspended from an overhead support. Fig. 2 shows my invention in use when not suspended. Fig. 3 is a perspective view of the apparatus unsuspended. Fig. 4 is a top plan view of the apparatus. Fig. 5 is a vertical longitudinal section on the line 5-5 of Fig. 4. Fig. 6 is a detail perspective view of the first registering mechanism detached from the receptacle or pan. Fig. 7 is a similar view to Fig. 6 of the second registering mechanism detached.

Referring now to the accompanying drawings, in which like numbers of reference indicate like parts in all of the figures, 1 designates the receptacle or pan proper, which comprises a conical bottom 1^a and side walls 1^b, which preferably are of greater diameter at the top than at the bottom for a purpose presently understood. At the upper edge of the side walls 1^b the pan has a horizontal rim 1^c secured to the walls 1^b in any approved manner, and the rim 1^c serves as a retaining means for the operating-ball 2 to prevent the ball flying out of the pan when the game is in operation. Secured to the wall 1^b of the pan 1 on the outside thereof is a bracket 3, having securing-ears 3^a, by means of which it may be riveted to the pan.

4 designates a disk or wheel which is pivotally mounted on a stud 5, secured to the outer end of the bracket 3, and the wheel or disk 4 is provided with peripheral ratchet-teeth 4^a and a plurality of radially-arranged pin-receiving apertures 4^b, spaced an equal angular distance apart. A stud-pin 6 co-operates with the apertures 4^b, as will be hereinafter more fully understood.

7 designates the operating-lever for the disk 4, which is fulcrumed, as at 7^a, on the bracket 3 and carries a pivoted pawl 8 at its wheel-adjacent end to engage the teeth 4^a of the disk 4 to impart motion to the disk 4 in one direction. The pawl 8 is held in engagement with the teeth 4^a by a spring 9, secured to a lug 7^b on the lever 7, as shown. The movement of the lever 7 is limited in one direction by a stop 10 on the bracket 3 and in the opposite direction by a lug 11, against which the spring 12 normally engages. The spring 12, which returns the lever 7 to its normal position, is secured to a second lug 7^c on the lever 7, as clearly shown in Fig. 6. A spring-catch 14, secured to the lug 14^a on the bracket 3, engages the peripheral ratchet-teeth 4^a to prevent the wheel 4 turning except in one direction. The lever 7 has its free end projecting within the pan 1 and has such end provided with a rod or handle 13, arranged substantially parallel with the pan side and transversely to the path of motion to the ball, the pan 1 being cut away, as at 1^x, to permit passage of the lever 7 and the handle 13, as shown.

15 designates a second bracket arranged near the bracket 3, which is provided with securing-ears 15^a, by means of which it may

be riveted or otherwise secured to the pan. The bracket 15 serves to support the second registering mechanism, which comprises a disk 16, of like form as the disk 4 and having 5 peripheral ratchet-teeth 16^a, as shown. The disk 16 is mounted to turn on a stud 15^b, secured near the outer end of the bracket 15. The disk 16 has indicating-numbers 16^b to 10 coöperate with a stationary pointer 16^c on the stud 15^b, as shown.

The operating-lever 17 for the second registering mechanism is fulcrumed on a stop 18^a, secured to the bracket 15, and carries a spring-pawl 19 at its disk-adjacent end, 15 which pawl 19 engages the ratchet-teeth of the disk 16 to move it in one direction, the disk 16 being prevented from movement in the opposite direction by a spring-catch 20, which engages the ratchet-teeth of the wheel 20 16 and is secured to a lug 15^x on the bracket 15. The operating-lever 17 projects through 25 an aperture 1^y in the pan to the inside thereof and is held in its normal position by a spring 21, secured to a lug 17^y on the lever 17, and has its free end in engagement with a lug 22 on the bracket 15. A pin or lug 23 limits the movement of the lever 17 in one direction, while the stop 22 limits its movement in the other direction, as will be seen by 30 reference to the drawings.

24 designates an apron secured to the pan 1 for protecting the registering mechanism, as shown. To enable my improved game to be conveniently operated and played, I may 35 suspend the pan 1 from an overhead support by means of cords 25, which pass through apertures 26 in the rim of the pan 1.

In the practical arrangement of my apparatus the first registering mechanism above 40 described is placed in such a position that its operating-lever will be engaged by the ball 2 as it passes on its path around the pan once in each revolution and is arranged to be operated in advance of the second registering 45 mechanism.

So far as described the manner in which my improved game is played and the apparatus operated is as follows: The pan may be either suspended from an overhead support, 50 as shown in Fig. 1, or it may be simply held in the hands of the operator. In either case the ball is placed in the pan and motion is imparted to the pan to cause the ball to run around the pan, and by reason of the slanting sides of the pan as the centrifugal force of the ball increases it will ride up the sides of the pan in proportion thereto. At each 55 revolution of the ball the same will engage the rod or handle 13 of the lever 7 and push 60 the lever 7 over to operate the disk 4 one notch for each revolution, and when the ball reaches a certain path in alinement with the lever 17 it engages the lever 17, pushing it over and turning the disk 16 one notch at

each engagement of the ball with the lever 65 17. The pin within the disk 4 is set to regulate the number of times the disk can be moved by the ball.

In playing my game the ball will always strike the handle 13 to operate the levers 7 in 70 advance of hitting the lever 17, so that the disk 4 will be moved one notch every revolution of the pawl, while the disk 16 is operated only at certain times, the object of the game being to cause the ball to operate the lever 17 75 and to record on the disk 16 the greatest number of times possible to a given number of times the ball engages the handle 13. Each disk 4 and 16, respectively, is preferably provided with the same number of 80 notches or teeth, so that should the ball strike the lever 17 every time it revolves the disk 16, as well as the disk 4, will make one complete revolution. Now supposing the game to be played is to register the greatest 85 number on the disk 16 during twenty revolutions of the ball, the operator places the pin in the position shown in Fig. 4 of the drawings, so that the disk 4 can move but twenty times before the pin engages the frame to 90 lock the first registering mechanism from operation. Thus it will be seen that the player has only a given number of revolutions of the ball in which to score by striking the lever 17, the objective point for the player to 95 land the ball being the lever 17, so as to score points. In starting to play the game the disk 16 of the second registering mechanism is set to zero and the pin is placed in the proper hole in the disk 4, as before stated. 100 After the requisite number of revolutions of the ball the disk 4 becomes locked, as before stated, and the handle 13 held projected within the pan, thus forming a stop for the ball to throw it out of the way, so that it cannot engage the lever 17 again so long as the lever 7 is locked, and thereby prevent unfair 105 playing of the game or cheating and ending the game so far as the particular player is concerned. The score is then indicated on 110 the disk 16 and can be readily determined by the pointer coöperating with the disk.

Having thus fully described the construction of my improved game apparatus and the manner in which it is operated and in which 115 the game is played, I claim—

1. A game apparatus comprising a receptacle, registering mechanisms secured thereto including operating-levers projecting within the receptacle, and a ball held within the 120 receptacle and adapted to operate said registering mechanisms when in motion, substantially as shown and described.

2. A game apparatus comprising a receptacle, a pair of registering mechanisms supported thereby and having operating-levers projected into the receptacle, one of said registering mechanisms having means for en- 125

- gaging with the ball during each revolution of the ball around the receptacle, substantially as shown and described.
3. A game apparatus comprising a receptacle, a pair of registering mechanisms supported thereby and having operating-levers projected into the receptacle, one of said registering mechanisms having means for engaging with the ball during each revolution of the ball around the receptacle, and the other registering mechanism having means engageable by the ball only at times, substantially as shown and described.
4. A game apparatus comprising a receptacle, registering mechanisms secured thereto, including operating-levers projecting within the receptacle, and a ball held within the receptacle and adapted to operate said registering mechanism when in motion, and means carried by the pan for retaining the ball therein.
5. A game apparatus comprising a receptacle, a pair of registering mechanisms supported thereby and having operating-levers projected into the receptacle, one of said registering mechanisms having means for engaging with the ball during each revolution of the ball around the receptacle, and means carried by the pan for retaining the ball therein.
6. A game apparatus comprising a receptacle, a pair of registering mechanisms supported thereby and having operating-levers projected into the receptacle, one of said registering mechanisms having means for engaging with the ball during each revolution of the ball around the receptacle, and the other registering mechanism having means engageable by the ball only at times, and means carried by the pan for retaining the ball therein.
7. A game apparatus comprising a receptacle, registering mechanisms secured thereto including operating-levers projected within the receptacle, and a ball held within the receptacle and adapted to operate said registering mechanism when in motion, said pan having means for normally positioning said ball against the sides of the pan substantially as shown and described.
8. A game apparatus comprising a receptacle, registering mechanisms secured thereto, including operating-levers projecting within the receptacle, and a ball held within the receptacle and adapted to operate said registering mechanism when in motion, means carried by the pan for retaining the ball therein, said pan having means for normally positioning said ball against the sides of the pan substantially as shown and described.
9. A game apparatus, comprising a recep-

tacle, a ball loosely held in said receptacle adapted to be rotated within the same, registering mechanisms secured to the pan and including operating-levers projected within the pan, and a hood or apron for protecting said registering mechanisms substantially as shown and described.

10. A game apparatus comprising a pan or receptacle, a plurality of registering mechanisms secured exteriorly thereto, and having operating-levers projecting within the receptacle, an operating device loosely held within the receptacle for engaging the operating-levers of the registering mechanisms as the operating device is moved around the receptacle and an apron secured to the receptacle for protecting the registering mechanism, substantially as shown and described.

11. A game apparatus of the class described, comprising the combination with a receptacle, of a pair of registering mechanisms secured exteriorly to the receptacle and including a registering-disk and operating-lever therefor, said operating-levers projecting within the receptacle, a ball within the pan for engaging the operating-levers of the registering mechanisms one at a time and an apron secured to the pan for projecting the registering mechanisms substantially as shown and described.

12. A game apparatus comprising a receptacle, registering mechanisms secured thereto, including operating-levers projecting within the receptacle, and a ball held within the receptacle and adapted to operate said registering mechanisms when in motion, and means for suspending the receptacle from an overhead support.

13. A game apparatus comprising a receptacle, registering mechanisms secured thereto, including operating-levers projecting within the receptacle, and a ball held within the receptacle and adapted to operate said registering mechanism when in motion, means carried by the pan for retaining the ball therein, and means for suspending the receptacle from an overhead support.

14. In a game of the class described, the combination with a first and second obstacle, of means for moving a ball in a circuitous path and causing it to engage one of said obstacles once during each movement of the ball through its path, and causing it to engage the other obstacle at times during its movement, and means for registering said engagements, substantially as shown and for the purposes described.
